Primary Examiner — Katherine A Holbrow*Assistant Examiner* — Riya Salil Kamat(74) *Attorney, Agent, or Firm* — Neal, Gerber & Eisenberg LLP(57) **CLAIM**

The ornamental design for a gaming machine, as shown and described herein.

DESCRIPTION

This application is related to the following commonly owned co-pending patent application: U.S. application Ser. No. 29/809,454, entitled: “gaming machine”.

FIG. 1 is a front perspective view of a gaming machine of our new design.

FIG. 2 is a front view of the gaming machine of FIG. 1.

FIG. 3 is a rear view of the gaming machine of FIG. 1.

FIG. 4 is a right side view of the gaming machine of FIG. 1.

FIG. 5 is a left side view of the gaming machine of FIG. 1; and,

FIG. 6 is a top view of the gaming machine of FIG. 1. The portions of the gaming machine shown in broken lines are not part of the claimed design.
